UNITED STATES PATENT OFFICE.

ALEXANDER T. MOORE, JR., OF NEW BEDFORD, MASSACHUSETTS, AND
HORACE A. FITCH, OF SCHENECTADY, NEW YORK.

DEVICE FOR SUPPORTING ELECTRIC LAMPS.

SPECIFICATION forming part of Letters Patent No. 400,473, dated April 2, 1889.

Application filed May 18, 1888. Serial No. 274,333. (No model.)

To all whom it may concern:

Be it known that we, ALEXANDER T. MOORE, Jr., of New Bedford, in the county of Bristol and State of Massachusetts, and HORACE A. FITCH, of Schenectady, in the county of Schenectady and State of New York, have invented a certain new and useful Improvement in Devices for Supporting Electric Lamps, of which the following is a specification.

10 This improvement relates particularly to supports for incandescent lamps. Quite commonly these lamps are suspended by the cable including the electric conductors. Often-times it is desirable when the lamps are so supported to adjust them vertically into different positions.

The object of the improvement is to provide a convenient means whereby lamps supported by a cable can be raised and lowered 20 at pleasure, so as to cause them to occupy any desired position.

The improvement consists in the combination, with a cable for suspending an electric lamp, of a rotary drum, to which such cable is 25 at one end attached and around which the cable may be wound, a counter-balance consisting of a spring within the drum or like device, means comprising dogs for retaining the drum in any position into which it may be adjusted, and metal side pieces, one of which has an opening for a stud on the bracket-arm and the other having a trunnion, whereby the two conductors or wires of the cable may be maintained in electrical communication with the 30 main wires of the electric system, notwithstanding the adjustment of the drum into different positions, all as hereinafter set forth.

In the accompanying drawings, Figure 1 is a side view of a device embodying our improvement. Fig. 2 is an inverted plan of the same, the cable at one point being shown in section.

Fig. 3 is a transverse section thereof.

Similar letters of reference designate corresponding parts in all the figures.

45 A designates a block, preferably made of insulating and non-combustible material. Two opposite sides are provided with grooves $a' a^2$, in order that they may receive the main wires in an electric system or branch wires 50 from such main wires. They also contain metallic plates $B' B^2$. The main wires, or the

branch wires extending therefrom, are connected with the plates $B' B^2$, so as to be in electrical communication therewith. These plates are provided with binding-screws $b' b^2$. 55

D' D² designate brackets which are secured by screws or otherwise to the block A and depend therefrom. Between these brackets a drum, C, is arranged. This drum consists of a body-piece, c, which is peripherally grooved, 60 and two plates or cheek-pieces, c' c². The body-piece c is preferably made of wood or other insulating material. The cheek-pieces, however, are made of metal. The cheek-piece c' is provided with a trunnion or axle, which 65 is journaled in the bracket D'. Opposite the trunnion or axle of the cheek-piece c' the cheek-piece c² is provided with a hole or bearing, into which extends a stud, d², with which the bracket D² is provided. The drum is free 70 to rotate, being supported partly by the trunnion of the cheek-piece c' and partly by the stud d² of the bracket D².

The body-piece of the drum has a central cylindric hole, c³, within it. As shown, this 75 hole extends entirely through it from side to side, and is covered by the cheek-pieces c' c². The cheek-pieces may be secured by screws or otherwise to the body-piece of the drum.

E designates a convolute spring arranged 80 within the hole c in the body-piece of the drum. The inner end of this spring is secured to the stud d² of the bracket D². The outer end is secured to the body-piece of the drum.

F designates a cable, which has its upper end secured to the drum and is coiled around the body-piece of the drum within its peripheral groove. When this cable is pulled downwardly, it rotates the drum, and so is 90 unwound from the drum. During this rotation the convolute spring is subjected to extra tension. When the drum is free to rotate in the reverse direction to that in which it is rotated by the pulling down of the cable F, the 95 spring E will exert a force sufficient to cause such reverse rotation.

The cable F contains two wires, f' f². It will be seen that these two wires are extended from the upper end of the cable in different 100 directions, and that they extend through the flanges or side walls of the peripheral groove

of the body-piece of the drum. Their extremities extend over to the metal cheek-pieces c' c^2 , and are secured by binding-screws g' g^2 .

5 It will be readily understood that by the construction which I have described electrical communication will be established between the two wires of the cable F and the main wires of the electrical system or with the 10 branch wires extending from such main wires, and that the rotation of the drum will in no respect disturb this electrical communication.

The cheek-piece c^2 has connected to its outer side two pawls or dogs, h. These pawls or 15 dogs are pivotally connected to the cheek-piece by means of screws or like devices.

The bracket D² is provided at the outer extremity of the stud d² with a disk-shaped flange, d⁴. In the upper part of this flange is 20 a notch.

Each of the pawls h is provided with a tooth adapted, when a pawl is above the flange d⁴, to drop into the notch of the latter. When the tooth of a pawl is thus engaged with the 25 notch, the drum will be kept from rotating.

It will be observed that the cheek-piece c^2 is provided at its circumference with a laterally-extending flange, c⁵. This flange prevents the pawls from swinging too far away 30 from the disk d⁴.

At the lower end of the cable an electric lamp, G, is arranged.

The force of the convolute spring E should be such as to preponderate over the weight 35 of the cable depending from the drum together with that of the suspended lamp, so that there will always be a tendency to rotate the drum in such direction as to wind up the cable. The tooth of each pawl is so shaped 40 that when the cable is pulled down the rotation of the drum will force the tooth of the pawl out of the notch in the disk d⁴, but so that the force of the spring operating to rotate the drum in the reverse direction will 45 not be capable of forcing the tooth out of such notch. It is obvious, therefore, that the lamp may always be lowered. If it is desired to raise the lamp, it will be necessary to first pull down the cable in order to disengage 50 the upper pawl from the disk d⁴, and then slacken the cable quickly, so as to permit of a rapid rotation of the drum under the influence of the convolute spring. When the

drum rotates rapidly, the pawls will be swung away from the disk by centrifugal force, and thereby kept out of engagement with the disk d⁴. Whenever the lamp is elevated to the desired position, the motion of the drum will be arrested by restraining the upward movement of the cable, and this will enable 60 one of the pawls to engage with the disk d⁴.

It will be seen that by our invention we produce a very simple and convenient device, whereby a lamp may be suspended and shifted into different positions without disturbing 65 the existing electrical conditions.

What we claim as our invention, and desire to secure by Letters Patent, is—

1. In a fitting for a pendent electric lamp, the combination of an insulated block or wall-piece, metallic bracket-arms depending therefrom, one of said bracket-arms having a bearing-stud and notched flange, the other bracket-arm having a bearing for a trunnion, wires connecting the main wires and the bracket-arms, a rotary drum having a recess, metallic side pieces secured to said drum, one of said side pieces having an opening for the stud of the bracket-arm, and the other of said side pieces having a trunnion, a spring connected at one end to the stud and at the other end to the drum within the recess, pivoted dogs automatically engaging the notch of the notched flange, and a cable secured to said drum and in electrical connection with the side pieces, substantially as specified. 70 75 80 85

2. In a fitting for a pendent electric lamp, the combination of an insulated block or wall-piece, metallic bracket-arms secured thereon, wires electrically connecting the main wires 90 and said bracket-arms, a rotary drum of insulating material having a central recess and metallic side pieces rotating therewith, one of said side pieces affording one of the bearings for said drum and a bracket-arm affording 95 the other bearing, a spring connected at one end to the axle and at the other to the drum, said spring being located within said central recess, and a cable secured to said drum and in electrical connection with said cheek-pieces, substantially as specified. 100
